SKATE ATTACHMENT

Edward George Jahnke, U. S. S. Wyoming,
New York, N. Y.

Application February 23, 1939, Serial No. 258,079

3 Claims. (Cl. 280—11.38)

This invention relates to improvements in skate attachments, and has particular reference to a device adapted to be secured to the runner of an ice skate, whereby the wearer may walk 5 upon any surface with comfort and ease, without in any way injuring the skate runner.

A further object is to produce a device of this character which may be quickly attached to the runner of a skating shoe while the user is in a 10 house, for instance, where there is the comfort of heat, and thereafter the wearer can travel the desired distance to the skating area.

A further object is to produce a device which is simple to manipulate, and one which will operate on either the right-hand or left-hand 15 skate with equal facility.

A further object of the invention is to provide means for securely clamping the skate runner to the device, whereby there may be no accidental slippage.

Other objects and advantages will be apparent during the course of the following description.

In the accompanying drawing forming a part of this specification and in which like numerals 25 are employed to designate like parts throughout the same,

Fig. 1 is a top plan view of my device;

Fig. 2 is a bottom plan view thereof;

Fig. 3 is a side elevation, showing an ice skate 30 in broken lines;

Fig. 4 is an enlarged fragmentary detailed view of one of the clamping screws; and

Fig. 5 is a cross sectional view taken on the line 5—5 of Fig. 1.

35 Ice skating is a healthful pastime when the sport may be enjoyed without suffering from the cold. It is the customary practice for skaters to carry their skating shoes and extra stockings to the skating area. Frequently they sit upon 40 the cold ground, snow or benches, remove the walking shoes and put on the cold skating shoes, and necessarily reverse the process when leaving the ice. In other words, the person skating may become chilled in going onto the ice and may 45 again become chilled when leaving the ice. With my device, it is merely a matter of quickly clamping the same to the runner of the skate and to proceed to one's destination.

In the accompanying drawing wherein for the 50 purpose of illustration is shown a preferred embodiment of my invention, the numeral 5 designates a plate rounded at both ends to conform with the average toe of a shoe. The bottom is also curved as shown at A and B, so that a person 55 walking will have no difficulty, as the plate will not give in the manner that an ordinary shoe would give; and, therefore, it is necessary that there be a rocking action for comfortable walking. The bottom of the plate is preferably 60 serrated, as illustrated in Fig. 2, to prevent slip-

page when walking upon the ground. Formed upon the plate is an upstanding rib 6 and a pair of upstanding lugs 7 and 8. These lugs carry threaded elements 9, upon the end of which is mounted a movable clamp 11. The threaded elements 9 may be attached to the clamp in any desired manner. In this particular instance, I have shown a groove 12 formed in the threaded elements 9 and a pin 13 carried in the clamp and engaging the groove 12.

10 It will be apparent that a person may readily place the runner of the skate between the clamp 11 and the rib 6, and by then rotating the threaded elements 9 with a suitable key wrench, the runner of the skate will be tightly gripped, 15 after which the user may walk to his destination with ease and without danger of turning the ankle or injuring the runner of the skate.

20 It is to be understood that the form of my invention herewith shown and described is to be taken as a preferred example of the same and that various changes relative to the material, size, shape and arrangement of parts may be resorted to without departing from the spirit of the invention or the scope of the subjoined claims.

25 Having thus described my invention, I claim:

1. A device of the character described, comprising an elongated plate having an upstanding rib approximately midway its width and extending the entire length thereof, upwardly extending lugs carried by the plate adjacent the ends thereof, screw bolts passing through said lugs, and a plate carried by the ends of the bolts approximately the same length as the rib, whereby the runner of a skate is clamped between said member and the upstanding rib throughout its 30 entire length.

2. A device of the character described, comprising a plate having the same contour at both ends, an upstanding rib formed on said plate and extending longitudinally throughout its length, upwardly extending lugs carried by the plate adjacent its end, screw bolts passing through said lugs, and a clamping plate carried by the inner ends of the screw bolts and adapted to clamp the 35 runner of the skate approximately throughout its length.

3. A device of the character described, comprising a plate having the same contour at both ends and an upwardly curved portion between the ends, an upstanding rib extending the entire length of the plate intermediate its sides, upwardly extending lugs carried by the plate adjacent its ends, a clamping plate between the lugs and the rib and parallel therewith, screw bolts 40 passing through the lugs and rotatably supporting the clamping plate, whereby the runner of the skate is clamped approximately throughout its length.
